CONVEYER OR CABLE CLAMP

Charles G. Dellenbach, Columbus, Ohio, assignor
to The Jeffrey Manufacturing Company, a cor-
poration of Ohio

Application February 26, 1937, Serial No. 127,928

8 Claims. (Cl. 198—176)

This invention relates to a conveyer or cable clamp and particularly to an improvement in devices of this type in which a separate key is formed to cooperate with the complementary members of the clamp to prevent any slipping of the cable with respect to the clamp.

Other objects of the invention will appear hereinafter, the novel features and combinations being set forth in the appended claims.

10. In the accompanying drawing,

Fig. 1 is a side elevational view of a portion of a cable carrying a pair of flights or clamps comprising my invention;

Fig. 2 is an enlarged end view of the flight or 15 clamp comprising my invention;

Fig. 3 is a longitudinal sectional view taken on the line 3—3 of Fig. 2, looking in the direction of the arrows;

Fig. 4 is a transverse sectional view taken on 20 the line 4—4 of Fig. 3, looking in the direction of the arrows;

Fig. 5 is an end view of a locking key prior to its final formation;

Fig. 6 is a side view of the key of Fig. 5 after 25 it has been finally formed;

Fig. 7 is a plan view of the key of Fig. 6; and

Fig. 8 is a perspective view of the key of Fig. 6.

Referring particularly to Fig. 1 of the drawing, there is seen a cable 10 which is a multiple strand flexible steel cable and may comprise the draft means of a scraper type of conveyer. Mounted upon the cable 10 at predetermined intervals is a plurality of flights or cable clamps 11, 11. It will be understood that in a complete cable conveyer there will be a plurality of flights 11, 11 spaced at equal intervals to cooperate with a large sprocket wheel to drive the cable 10. In some instances the flange portion of alternate flights 11 will be eliminated which will, in effect, convert said flights into transmission blocks. It may be stated that transmission blocks are employed in a scraper type of conveyer for the purpose of insuring proper driving of the cable 10 from the drive sprocket where it is not desirable to have all conveying flights.

Each of the flights 11 comprises a clamp member or casting 12 provided with a longitudinally extending groove 13 which is straight and of uniform diameter, thereby receiving the cable 10 without bending or deforming said cable 10.

Cooperating with the clamp member 12 is a complementary clamp member or casting 14 provided with a longitudinally extending tongue 15 adapted to extend into the groove 13 and to

cooperate with said groove 13 to effect a clamping action on the cable 10. As is clearly illustrated in Fig. 2 of the drawing the cable contacting face 16 of the tongue 15 is a segment of a cylinder whereby it will contact a plurality of strands of the cable 10 without effecting an appreciable deformation thereof.

The clamp members 12 and 14 are provided with abutment head members 17 and 18, respectively, at each end, which head members 17 and 18 cooperate to provide abutment means which cooperate with the drive sprocket to drive the cable conveyer. By virtue of the substantially duplicate arrangement of the head members 17 and 18 at each end of the flights 11 it is evident that said flights 11 may be clamped to the cable 10 in either of two reverse positions whereby should one pair of head members 17, 18 become worn the flights may be reversed to present a new pair for active service.

Centrally disposed with respect to the clamp members 12 and 14 I provide a pair of complementary webs or flanges 19 and 20, carried by the clamp members 12 and 14, respectively. It is manifest that said flanges 19 and 20 cooperate to provide a substantially continuous disc-like flight which, in operation, may move in a trough to convey material by a scraping action in a well-known manner.

Extending through the clamp members 12 and 14 is a plurality of bolts 21, four in number, provided with appropriate nuts 22. It is evident that the nuts 22 may be screwed home to clamp the members 12 and 14 together, whereupon the tongue 15 will effect a clamping action on the cable 10 with the grooves 13.

I have found from practice that the device of the type so far described is reasonably satisfactory, but that under very high load there may be a tendency for the flight or cable clamp 11 to slip with respect to cable 10. In order to increase very appreciably the force necessary to cause this slipping I provide an additional clamp means or wedge in the form of a key 22. I have found from actual test that the key 22 more than doubles the force necessary to effect a slipping of the flight or cable clamp 11.

Centrally positioned in the longitudinally extending tongue 15 of the clamp member of casting 14 is a groove or recess 23 which has a flat top surface 24. This groove is positioned opposite the cable 10 and receives the key 22. The key 22 is formed to have an arcuate surface 25 which contacts the top surface 24. As a consequence said key 22 may rock or pivot on the top

surface 24 which will cause one end thereof to dig into the cable 10, thereby effecting a very complete clamping or wedging action thereon.

In order to enhance further the wedging or clamping action effected by the key 22 I provide a particular form of cable contacting surface 26 therefor. As clearly illustrated in Fig. 5 of the drawing, the key 22 is originally made with the cable contacting surface 26 as a segment of a cylinder, the diameter of which is substantially the same as the cable 10. Thereafter, said surface 26 is formed with a plurality of diagonal grooves 27 which follow lines substantially along the axis of the individual strands of the cable 10. The diagonal grooves 27, of course, inherently produce diagonal ridges 28 on the surface 26. It will be evident that this particular corrugated formation of the cable contacting surface 26 provides a surface of the type which will have intimate contact with the strands of the cable 10 thereby increasing to a maximum the contacting area between said surface 26 and the cable 10.

The thickness of the key 22 is so selected that the tongue 15 to both sides thereof will have an appreciable clamping action on the cable 10 while at the same time an appreciable amount of clamping action will be effected on said cable 10 by the key 22.

In case the device comprising my invention is intended to be used only as a transmission block rather than a flight the webs or flanges 19 and 20 will be eliminated, otherwise the structure will be substantially the same as that above described.

The key 22 may be formed as a drop forging of steel and, if desired, may be given a hardening treatment. It is also possible to form the key 22 by milling the grooves 27.

In the operation of the device comprising my invention the flights or cable clamps 11 will be rigidly clamped to a cable 10 at predetermined intervals. This clamping action will, of course, be effected by screwing down the nuts 122 on bolts 21. The tongue 15, which is formed substantially in two parts, will, with the groove 13, effect a clamping action on the cable 10. A supplementary clamping action will be effected by the key 22 which will have very intimate contact with the cable 10 due to the corrugated formation of the surface 26. Should there be any tendency for slippage between a flight 11 and the cable 10 during operation the key 22 will rock or pivot on its surface 25, thereby digging into the cable 10 and effecting a very thorough wedging action. As before stated, in practice it has been found that this particular construction more than doubles the effective clamping action on the cable 10.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. A rope clamp comprising a pair of separable members one of which is provided with a rope receiving groove, the other of which has spaced-apart rope gripping members extending into said groove with a recess between said gripping members, a clamping element positioned in said recess between said rope gripping mem-

bers, said clamping element having a rope clamping surface formed with ridges and grooves to make intimate gripping contact with the irregular surface of a multiple strand rope, and means for clamping said members together to effect a clamping action between said gripping members and the rope and between said clamping element and the rope. 5

2. A rope clamp comprising complementary members one of which is provided with a groove 10 and the other with spaced-apart rope gripping tongues adapted to extend into said groove, said groove and tongues being adapted to co-operate to grip a rope, spaced-apart devices for clamping said members together with the tongues gripping the rope in said groove, and a rocking supplementary gripping element in a recess in one of said members between said clamping devices in position to aid in clamping said members to the rope, the construction and arrangement being 20 such that the clamping action of the rocking supplementary gripping element co-acts with the clamping action of the gripping tongues to clamp said complementary members to the rope without appreciable bending or deformation of the 25 latter.

3. A rope clamp comprising complementary members one having a straight rope receiving groove and the other having spaced-apart rope gripping tongues adapted to extend into said groove, the member having the tongues being provided with a recess between said tongues and opposite the groove in the other member, a key in said recess having grooves and ridges providing an intimate rope contacting surface to clamp 30 a multiple strand flexible rope, and a plurality of devices for connecting said complementary members to cause said spaced-apart tongues and the key between the same to grip the rope against 35 said groove. 40

4. In combination, complementary members one having a straight uniform rope receiving groove and the other having spaced-apart rope gripping tongues opposite said groove, an enclosed recess extending longitudinally along one of said members intermediate the ends thereof, a rope fitting into said groove, means for clamping said spaced-apart tongues against said rope, and a key mounted for rocking movement in said recess in position to grip said rope with a wedging action when said rope tends to slip relatively to said spaced-apart rope gripping tongues. 50

5. In a device of the class described, the combination with a rope, of a pair of complementary clamp members one having a rope receiving groove and the other spaced-apart rope gripping tongues adapted to extend into said groove, a removable locking key in a recess between said spaced-apart rope gripping tongues in position to grip the rope between the tongues and sufficiently free to rock relative to said recess while confined therein to effect a wedging gripping action on the rope when the latter tends to slip relatively to said gripping tongues, and means for clamping the members together with said tongues and said removable locking key in gripping connection with the rope in said groove. 60 65

6. In a conveyer, the combination with a flexible rope of the multiple strand type, of a sectional flight, a pair of complementary members for carrying the sections of said flight, one of said members having an elongated body with a straight uniform rope receiving groove and the other member having spaced-apart rope gripping tongues extending into said groove, means for clamping 70 75 80 85 90 95 98

said complementary members together to effect a clamping action on said rope between said tongues and said groove, the tongue carrying member having an enclosed recess between said tongues 5 and having a rectangular elongated inner wall spaced from the rope in the groove and extending longitudinally thereof, and a removable key extending into said recess and having a gripping face provided with a corrugated surface conforming to the strands of said rope for intimate gripping contact therewith, said key having a curved back adapted to have rocking engagement with the rectangular inner wall of the recess to enable 10 said key to have a clamping action on the rope supplementary to that of the gripping tongues when the rope tends to slip relatively to said 15 tongues.

7. In a conveyer, the combination with a flexible rope, of a sectional transmission block comprising complementary sections, one member having a rope receiving groove and the other having means co-operating with said groove to grip said rope, means for clamping said sections together to effect a clamping action on the rope between 20 said gripping means and said groove, one of said sections having an enclosed recess with an inner 25

wall extending longitudinally of said groove and parallel thereto, and a key corrugated on one side to fit the rope and curved on the opposite side for rocking engagement with said rectangular inner wall of said recess, the construction and arrangement being such that the enclosed recess constitutes the sole means for confining the key therein when the clamping means holds together said complementary sections as aforesaid.

8. A rope clamping device comprising complementary members one having a groove for receiving a rope and the other having rope gripping means extending into said groove, the member having the rope gripping means being provided with an inner enclosed recess having an inner elongated wall extending longitudinally of said groove and in parallelism therewith, a key in said recess and having a corrugated face adapted to grip the rope in the groove and also having a curved back in rocking engagement with said inner elongated wall, and two pairs of bolts for securing together said complementary members when said rope is in said groove and said key is confined in said recess.
